UNITED STATES PATENT OFFICE.

LOIS M. JONES, OF GRAND RAPIDS, MICHIGAN.

COMBINED UNDERWAIST AND GARMENT-SUPPORTER.

SPECIFICATION forming part of Letters Patent No. 752,343, dated February 16, 1904.

Application filed June 1, 1903. Serial No. 159,437. (No model.)

To all whom it may concern:

Be it known that I, Lois M. JONES, a citizen of the United States, residing at Grand Rapids, in the county of Kent and State of Michigan, have invented certain new and useful Improvements in a Combined Underwaist and Garment-Supporter; and I do hereby declare the following to be a full, clear, and exact description of the invention, such as will enable others skilled in the art to which it appertains to make and use the same.

My invention relates to improvements in a combined underwaist and garment-supporter; and its object is to provide an underwaist of elastic material with suitable means for attaching and supporting the outer garments and sanitary appliance, whereby the weight of the articles so supported will be sustained by and upon the shoulders of the wearer; to provide a device, as aforesaid, that will not interfere with the free movement of the wearer and that will not in any way restrict the action of the muscles and internal organs of the wearer, and to provide the device with certain new and useful features, hereinafter more fully described, and particularly pointed out in the claims.

My invention consists, essentially, of a body-garment or underwaist of suitable form and of freely-yielding material, preferably of a knit fabric, and various tapes or straps of substantially longitudinally inelastic or unyielding material extending in loops over the shoulders and thence downwardly and rearward thereon and secured thereto, and various means for attaching the various outer and nether garments and sanitary appliance to said tapes or straps, as will more fully appear by reference to the accompanying drawings, in which—

Figure 1 is a front view of a device embodying my invention arranged as worn; Fig. 2, a rear view of the same; Fig. 3, an exterior view of the entire structure opened out flat or in plan view, and Figs. 4 and 5 details of the skirt-support and shirtwaist-holder.

Like letters refer to like parts in all of the figures.

A represents an underwaist or body-garment of any suitable freely-yielding material,

preferably some suitable knit fabric, and fitting the body of the wearer closely and yielding freely to any movement thereof.

B, C, D, E, F, and G represent various strips of flexible and longitudinally unyielding material, preferably consisting of suitable tapes or strips of woven fabric and secured to the garment A by sewing the edges of the said tapes thereto. The tapes B extend close to each other and vertically upon the lower part of the middle back portion, and thence upward and diverging away from each other extend over the shoulders and downward upon the front, converging somewhat toward each other, as shown, and secured to the garment throughout on the back and on the front down to a little below the waist-line, as at B', and thence detached and prolonged downward any convenient distance, as at B''. At B' another tape C is attached by one end only and extends downward substantially the same distance as the tape B''. Attached to the outwardly-curved back portions of the tapes B and extending downward at each side thereof are two other tapes F F, which are secured to the back of the garment down to F', and thence are detached and extend downward, as at F''. To these extended portions C, B'', and F'' may be attached by buckles, safety-pins, or other suitable fastenings any suitable hose-supporters and sanitary appliance, (not shown,) which will thus be supported from the shoulders of the wearer by means of the tapes B.

If preferred, the tapes F may be omitted and the tapes B prolonged downward instead; but the construction shown is preferable and more substantial.

D D are other tapes extending up the back near each side thereof, and diverging outward toward the top also extend over the shoulders and thence down the front a short distance and converging inward to the point D', whence they are turned abruptly to a horizontal direction and meet at the front. These tapes are secured to the garment throughout, and the horizontal portions D'' are made slack or full to provide for the yielding or expanding of the garment to a certain limited extent to permit free breathing of the wearer.

A transverse tape G at the back arranged

horizontally and opposite the tapes D" connects the tapes B B and is also left full or slack in like manner and for the same purpose as are the portions D". Under each arm opening and extending diagonally from the upper part of the tapes B to the lower back part of the tapes D are tapes E, which, together with the tape D, serve to constitute loops extending over the shoulders and to the bottom of the garment at each side of the back thereof. The tapes B also constitute suspending-loops extending over the shoulders, and are also inclined backward and downward, whereby they tend to draw the shoulders backward, thus acting as shoulder-braces as well. All of these tapes serve to retain the shape of the undergarment and at the same time have a limited relative movement due to the elasticity of the said garment. Attached to these several tapes at or near the waist-line are buttons K, which serve to attach skirts or other garments.

For a support to the outer skirt and to engage and hold a shirt-waist detachable studs J J are provided, which studs are mounted on the respective ends of a plate I of suitable rigid material, preferably celluloid or metal, and this plate is detachably secured to the tapes B at or near the middle of the back by means of a suitable pocket or receptacle H, within which the plate I is inserted with its respective ends projecting oppositely therefrom and the studs J projecting outward.

Whenever the garment is to be washed, this plate is readily detached by withdrawing it endwise from the pocket, and when in use the studs retain it in place therein.

Having thus fully described my invention, what I claim, and desire to secure by Letters Patent, is—

1. The combination of an elastic underwaist, longitudinally unyielding tapes attached thereto, two of said tapes extending vertically and close together upon the lower middle portion of the back and thence diverging outward and extending over the shoulders and thence downward on the front; two other tapes extending vertically along the outer portions of the back and thence over the shoulders, and thence downward and converging on the front, and thence extending horizontally across the front, and garment-supporting means attached to said tapes near the waist-line.

2. The combination of an elastic underwaist, longitudinally unyielding tapes attached thereto and extending vertically and near each other at the lower back portion of the waist, thence diverging outward and extending over the shoulders, and thence downward on the front, garment-supporting means attached to said tapes, a plate detachably secured to the middle back portion of said tapes, and outwardly-projecting studs on the respective ends of said plate.

3. The combination of an elastic underwaist,

longitudinally unyielding tapes attached thereto and extending in diverging curved lines from the middle of the back and over the shoulders and thence downward on the front side, garment-supporting means attached to said tapes, a pocket attached to said tapes near the middle back portion of the garment, a plate detachably inserted in the pocket and oppositely projecting therefrom, and rearwardly-projecting studs mounted on the respective ends of said plate.

4. The combination of an elastic underwaist, longitudinally unyielding tapes secured thereto and extending in diverging lines from the middle back portion over the shoulders and thence downward on the front side thereof, and extended below the waist at the front, tapes attached to the diverging rear portions of said first-named tapes and thence extending downward below the waist at the rear, garment-supporting means attached to said tapes near the waist-line, a pocket attached to said first-named tapes near the middle back portion of the waist, a plate inserted in the pocket and projecting therefrom at each end, and studs on the respective ends of said plate and projecting rearward therefrom.

5. The combination of an elastic underwaist, longitudinally unyielding tapes secured thereto, and extending upward at the middle of the back and thence diverging and extending over the shoulders, and thence downward, and prolonged below the waist at the front, like tapes attached to the diverging back portions of the same and extending below the waist at the rear, like tapes extending upward on the side portion of the back, and thence over the shoulders and in downward converging lines on the front and thence turned at obtuse angles and extending horizontally across the front, a horizontal tape connecting the diverging rear portions of the first-named tapes, said horizontal tapes all being longitudinally slack or full to permit limited expansion of the waist, and garment-supporting means attached to the vertical tapes near the waist-line.

6. The combination of an elastic underwaist, longitudinally unyielding tapes attached thereto, and extending in curved diverging lines from the middle back portion over the shoulders, thence downward on the front, other like tapes extending upward and outward in curved lines along the side portions of the back and over the shoulders, and thence downward and horizontally across the front, tapes extending diagonally beneath the armholes and connecting the front and rear tapes, and garment-supporting means attached to the tapes near the waist-line.

7. In combination with an elastic underwaist, tapes attached thereto, and extending over the shoulder and downward at the front and rear thereof, garment-supporting means attached to said tapes near the waist-line, a pocket attached to said tapes near the

middle back portion thereof, a plate detachably inserted in said pocket and projecting therefrom at each side and studs on the respective ends of said plate and projecting 5 rearwardly therefrom.

8. The combination of an elastic underwaist, tapes attached thereto as follows: a pair extending vertically and close together on the lower back portion and thence diverging outward and over the shoulders and thence downward along the front and extending below the same; a second pair extending along the outer sides of the back in diverging lines and over the shoulders and thence downward and inward 15 on the front and thence turned at an obtuse angle and extended loosely across the front, two other tapes attached to the diverging

back portions of the first-named tapes and thence extending downward below the waist, two tapes extending diagonally beneath the 20 armholes and connecting the front and rear tapes, garment-supporting means attached to the tapes near the waist-line, a pocket attached to the middle back portion of the first-named tapes, a plate detachably inserted in 25 the pocket and projecting therefrom at each end, and studs on the ends of said plate and projecting rearward therefrom.

In testimony whereof I affix my signature in presence of two witnesses.
